US00D755809S

(12) **United States Design Patent**
Kim et al.

(10) **Patent No.:** US D755,809 S
(45) **Date of Patent:** ** May 10, 2016

(54) **DISPLAY SCREEN OR PORTION THEREOF
WITH GRAPHICAL USER INTERFACE**

(71) Applicant: **Samsung Electronics Co., Ltd.**, Suwon-si, Gyeonggi-do (KR)

(72) Inventors: **Young Sun Kim**, Suwon-si (KR); **Heui Jin Kwon**, Seongnam-si (KR); **Jun Sik Choi**, Suwon-si (KR); **Su Gyeong Hyeon**, Daegu (KR)

(73) Assignee: **Samsung Electronics Co., Ltd.**, Suwon-Si (KR)

(**) Term: **14 Years**

(21) Appl. No.: **29/495,148**

(22) Filed: **Jun. 27, 2014**

(30) **Foreign Application Priority Data**

Dec. 30, 2013 (KR) 30-2013-0066099

(51) **LOC (10) Cl.** **14-04**

(52) **U.S. Cl.**

USPC **D14/485**

(58) **Field of Classification Search**

USPC D14/485–488; D20/11, 27, 39

CPC .. G06F 3/048–3/0497; H04N 5/232–5/23296

(57) **CLAIM**

We claim, the ornamental design for a display screen or portion thereof with graphical user interface, as shown and described.

DESCRIPTION

The FIGURE is a front view of a display screen or portion thereof with graphical user interface showing our new design. The broken lines illustrate a display screen or portion thereof and its environment, as well as portions of a graphical user interface, and form no part of the claimed design.
